UNITED STATES PATENT OFFICE.

PAUL M. TEBBS, OF HARRISBURG, PENNSYLVANIA.

ELECTRICAL CONTACTOR.

Application filed December 1, 1924. Serial No. 753,987.

This invention relates to improvements in electrical contactors and it consists of the constructions, combinations and arrangements herein described and claimed.

- 5 An object of the invention is to provide an electrical contactor of a construction permitting bringing the conductor wire into direct engagement with the contact point or surface of an electrical device.
- 10 Another object of the invention is to provide an electrical contactor in the nature of a clip to which the conductor wire is so applied that direct contact of the contact point or surface of an evacuated vessel or tube as used for radio receiving, broadcasting or lighting may be obtained.
- 15 Another object of the invention is to provide an electrical contactor by the use of which the usually numerous contact pieces and conductors in a large variety of electrical devices may be eliminated, thereby working an economy by reducing current losses and further, simplifying and reducing the work of assembling parts.
- 20 Another object of the invention is to employ deformed wire in connection with the contactor for the purpose of establishing a contact surface.
- 25 Other objects and advantages will appear in the following specification, reference being had to the accompanying drawings, in which

Figure 1 is a sectional view of a radio tube socket illustrating one of the contactors.

- 30 Figure 2 is a plan view of the socket, parts being shown in section as it would appear substantially on the line 2-2 of Figure 1.
- 35 Figure 3 is a plan view of the contactor blank before bending.

Figure 4 is a detail perspective view of the contactor bent into the shape that it finally assumes when incorporated in the socket.

- 40 Figure 5 is a detail perspective view of the middle nut used in connection with the contactor.

Figure 6 is a detail perspective view of the deformed wire used in connection with the contactor.

- 45 Figure 7 is a detail section on the line 7-7 of Figure 2.

Figure 8 is a plan view in which enough is shown in section to disclose the position of one of the contactors, the construction being that of a modification.

Figure 9 is a detail section on the line 9-9 of Figure 8.

Figure 10 is a detail perspective view of the modified form of contactor.

Figure 11 is a detail perspective view of the deformed wire used in connection therewith.

Figure 12 is a plan view of the blank from which the modified contactor is bent.

As already stated, the purpose of the invention is to provide a contactor by means of which the electrical conductor is brought nearer to the surface with which it is to contact, in fact is brought into actual contact with such surface. The contactor is bent up out of a blank such as shown in Figure 3. The blank is made of a suitable conducting material, usually copper, brass or the like, and it is stamped out of sheets of the material by means of suitable machinery.

The blank body 1 is crimped or scored at 2 to define what later becomes the clip end 3. Both the blank body and clip end have holes 4 and 5 respectively these obviously align when the contactor is fitted upon the screw 6 (Fig. 1) of the binding post. There is a notch 7 at one side of the blank body for the purpose of receiving the lug 8 of the middle nut 9.

Extending from the blank body is a shank 10. The shank is narrower than the blank body thereby preventing an offset arrangement of the shank in respect to the blank body. This arrangement, as will later appear, is for the purpose of centering the wire or other conductor in respect to the contactor. The shank has a pair of lateral or side lugs 11, and an end lug 12. These various lugs have crimping lines or scored places 13 and 14 respectively to permit bending up into final shape. The final shape of the contactor is well shown in Figure 4, but here both the wire and the middle nut are omitted.

Use is made of a deformed wire 15 (Fig. 6) to aid in the intended function of the contactor. This wire may either be square as shown or it may be round, but in any event one end is flattened at 16 to provide a rather broad contactable surface. The flattened end 16 provides an ample contactable surface, and in practice is preferably either plated or tinned to provide the best contact, it being necessary only to treat 110

the deformed end and not apply the treatment to the whole wire.

Reference is now had to Figures 1 and 2. 17 is to be regarded as a conventional socket for holding the base 18 of a radio tube 19, whether the tube be of the type for receiving or transmitting. The use of the invention is not confined to radio work, but may be extended to an innumerable variety of other electrical appliances. The base 20 of the socket carries a plurality of binding posts (usually four) of which the screw 6 is the only one herein shown or mentioned. The other three contactors will be identical with 15 the one already described.

The screw 6 is inserted in the base 20 from the underside and is screwed through the clip end 3, middle nut 9 and blank body 1, the latter having been appropriately bent on 20 the scored lines 2 to enclose the middle nut and reach the position shown in Figure 1. The deformed wire 15 is held upon the contactor by bending the side lugs 7 and the end lugs 12 over the flattened end 16 as shown. 25 The wire passes one side of the screw 6 (Fig. 2), a washer 21 and thumb screw 22 being used to clamp the wire down upon the contactor.

The engagement of the lug 8 of the nut 9 30 with the notch 7 in the blank body 1 prevents the nut from turning. The contactor thereby incidentally provides a nut lock. It is to be noted that, as hereinbefore, the wire 15 assumes a central position in respect 35 to the shank 10. It is necessary that the wire 15 pass to one side of the screw 6. The shank 10 is therefore offset in relation to the blank body so that the wire may be centralized as desired. The shank 10 passes 40 through an opening 23 in the socket 17. The tube base 18 has a plurality of prongs of which only the prong 24 is shown in the drawings. Upon inserting the tube in the socket the prong 24 engages the contactor 45 making a direct electrical contact between the wire 15 and the terminal of the tube. By virtue of the fact that the contactor extends out an appreciable distance from the screw 6 upon which it is mounted, the free 50 end possesses a sufficient degree of resiliency to insure tight engagement with the prong or terminal 24.

The modification in Figures 8 to 12 is the same as the foregoing form in principle but 55 is slightly different in structure. The body 1^a is scored at 2^a defining what later becomes the clip end 3^a, the body and clip end having openings 4^a and 5^a for the reception of the screw 6^a as before. The notch 7^a receives the 60 lug 8^a of the middle nut 9^a. The shank 10^a is scored at 25 to permit a rather peculiar twisting of the shank so that the position in Figure 10 may be assumed.

Scored places 26 provide for bending the 65 extremity of the shank so as to produce a

head 27 (Fig. 10) the remaining part of the shank being shaped into a spring clip 28 by which the prong or terminal 24^a is held against the flattened end 16^a of the wire 15^a in the manner shown in Figure 8.

It is optional whether the wire 15^a be merely flattened as proposed in Figure 6 or whether it be left with a tip 29 as shown in Figures 8 and 11. In the latter instance the head 27 is provided with a hole 30 so that the tip may project through and thereby insure the holding of the flattened but otherwise free end of the wire. The main part of the shank 10^a is held in the horizontal plane but it is given both a quarter twist and is bent at 70 the place where it passes through the opening 23^a in the tube socket 17^a. The wire 15^a is also bent at the base of the flattened portion 16^a. The spring clip 28 restricts the passage for the prong 24^a, and when the tube 75 is appropriately turned the prong can be forced in but will then be held against the flattened surface of the wire by the resiliency of the spring clip.

It is estimated that bus wire with flattened portions (so called deformed wire) 80 can be manufactured and sold at but a slight additional cost. The advantages of employing such wire in the manner disclosed 85 will greatly simplify the installation of electrical connections in devices such as cited and many other designs. The contactor eliminates the need for the soldering lugs now so commonly used, and furthermore it provides a means for holding the conductor wire 90 at the place of contact with utmost reliability. The wire will not work loose as it sometimes does with the ordinary binding posts.

In conclusion, it must be stated in connection with the modification that undefor med wire may be used equally as well as deformed wire. In other words, wire that has not 95 been flattened may be used as well as wire that has been flattened. In this case the end 100 of the wire is merely bent to take the corner at 25 (Fig. 10) the free end being inserted in the hole 30 which then serves to stabilize the bent end. The opening in the tube socket 105 must be large enough to admit the head 27, 110 and when the head is admitted the rest of the contactor may be fixed upon the socket base 115 in the manner already described in connection with Figure 1.

While the construction and arrangement 120 of the improved contactor is that of a generally preferred form, obviously modifications and changes may be made without departing from the spirit of the invention or the scope of the claims.

I claim:

1. The combination of a socket having an opening, an electrical conductor including a wire, and a support mounted upon the socket, extending through the opening and holding 130

- a portion of the wire in position for direct contact by an appliance inserted in said socket, said support having means with which the wire engages for stabilization.
- 5 2. The combination of a socket having an opening and a base, an electrical conductor including a wire extending through the opening, a contactor extending through the opening and providing a support for a portion of the wire in position for direct contact by an electrical appliance inserted in the socket, said contactor having means by which the wire is held, and a binding post by which the contactor is held upon the base 10 and by which the wire is clamped against the contactor.
- 15 3. A contactor comprising a blank body with a notch, a clip end bent down and under the body, a nut situated between the body and clip end having a lug occupying the notch, a binding post including a screw 20 passing through the nut and appropriate openings in said body and a shank extending from the body and having an off center relationship to said body, and side lugs 25 adapted to be bent over upon a wire.
4. A contactor comprising a blank body with a notch, a clip end bent down and under the body, said clip end and body having registering openings, a shank extending 30 from the body and having an off center relationship to said body, and lugs formed at the sides and extremities of the shank.

PAUL M. TEBBS.
